UNITED STATES PATENT OFFICE.

CHARLES CAULOW PINCKNEY, OF VALDOSTA, GEORGIA, ASSIGNOR OF ONE-HALF TO THOMAS W. TERRY, OF SAME PLACE.

FIFTH-WHEEL FOR VEHICLES.

SPECIFICATION forming part of Letters Patent No. 335,088, dated January 26, 1886.

Application filed October 16, 1885. Serial No. 180,074. (No model.)

To all whom it may concern:

Be it known that I, CHARLES C. PINCKNEY, a citizen of the United States, residing at Valdosta, in the county of Lowndes and State of Georgia, have invented certain new and useful Improvements in Fifth-Wheels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to new and useful improvements in fifth-wheels for wagons or other vehicles, and has for its object the provision of a device simple in construction, durable, and at the same time cheaper than the ordinary fifth-wheels now in use.

20 My invention consists of a circle or guide formed with annular grooves on its inner and outer peripheries, the interior one receiving the center or circular portion of the fifth-wheel to which the bolster is secured, and the exterior one receiving the curved reach, which extends around it and furnishes the means for both coupling the fore and hinder parts of the running-gear, and for permitting 25 them to turn independently of each other. This construction enables me to dispense entirely with the king-bolt.

The fifth-wheel is fastened to the front axle by means of bolts which pass through the circle or guide, leaving the center free to work 30 in the inner groove of said guide or circle.

Reference is made to the accompanying drawings, which illustrate what I consider the best means for carrying my invention into 35 practice.

Figure 1 is a plan view of a running-gear having my device applied. Fig. 2 is a central longitudinal section of my device.

Similar letters of reference indicate corresponding parts in all the figures in which they occur.

A is the center or circular portion of the fifth-wheel working in the inner groove of the circle or guide B and resting on the lower por-

tion of said guide. The center A has two upright arms, a a, which connect it to the bolster of the wagon.

The opening in the upper portion of the circle or guide B is made larger than that in the lower portion, so as not to obstruct the course of said upright arms a a, in which the bolster b* is held. This circle or guide B is made of two separate pieces, with a ring or filling between them, and thus forming the interior groove for receiving the center A, and the exterior groove in which the curved reach or coupling-pole D works; or it may be made of one solid piece, with means for receiving the center A, as may be desired. The reach or coupling-pole D works in the outer groove of the circle or guide B and connects it with the rear axle of the vehicle. It is preferably made in a single piece.

The reach is preferably made in one continuous piece, extending from the rear axle, near one end, forward and around the guide and back to the rear axle, near the other end. This makes a simple, strong, and reliable construction.

The circle or guide is fastened to the front axle by means of the bolts b b, and in such manner as not to interfere with the working of the center A.

Having thus described my invention, what I desire to claim and secure by Letters Patent is—

1. In a fifth-wheel, the combination, with the interiorly and exteriorly grooved guide, of the reach encircling and resting in the exterior groove of said guide, and a revoluble center working in the interior groove, as set forth.

2. In a fifth-wheel, the combination, with the exteriorly and interiorly grooved circle or guide, of the reach or coupling-pole bent, as described, in front to work in exterior groove and the center working in the interior groove of said circle or guide, and having two upright arms to engage with the bolster of the wagon, as set forth.

3. In a fifth-wheel, the combination, with the center, of the circle or guide, the under plate extended inward beyond the upper plate

and supporting the center, as and for the purpose set forth.

4. The herein-described circle or guide for fifth-wheels, having an exterior groove to receive the reach or coupling-pole and an interior groove to receive the rotatable center, as described, said circle or guide being bolted to the front axle, substantially as and for the purpose set forth.

In testimony whereof I affix my signature to in presence of two witnesses.

CHARLES CAULOW PINCKNEY.
